INDICATOR DIAL FOR A RADIO OR THE LIKE

Melvin H. Boldt, Glenview, Ill., assignor to Zenith Radio Corporation, Chicago, Ill., a corporation of Delaware

Filed Jan. 22, 1962, Ser. No. 68,394

Term of patent 7 years

(Cl. D56—4)

FIG. 1

FIG. 2

FIG. 3

FIGURE 1 is a front elevational view of an indicator dial for a radio or the like showing my new design;

FIGURE 2 is an enlarged front elevational view; and FIGURE 3 is a sectional view taken on the center of FIGURE 2.

The broken line showings of a radio panel in FIGURE 1, the indicator dial rim in FIGURE 2 and the fragmentary showing of a radio panel in FIGURE 3 are for illustrative purposes only.

The dominant features of my design reside in those portions shown by means of full lines. The three indicator dots illustrated in FIGURES 1 and 2 are formed from an internal light source when electric power is turned on

and the positions of the dots are variable through the index lines of their respective scales. They are indicated in the positions shown by means of broken lines for illustrative purpose only.

I claim:

The ornamental design for an indicator dial for a radio or the like, substantially as shown and described.
